DESIGN FOR MOLDED ICE CREAM

Elmer J. Mather, Chevy Chase, Md.

Application March 21, 1934, Serial No. 51,124

Term of patent 14 years

To all whom it may concern:

Be it known that I, ELMER J. MATHER, a citizen of the United States of America, and a resident of Chevy Chase, Maryland, have invented a new, original, and ornamental Design for Molded Ice Cream, of which the following is a specification, reference being had to the accompanying drawing, forming part thereof, in which drawing Fig. 1

is a perspective view and Fig. 2 is a front view of the molded ice cream embodying my new design.

I claim:

The ornamental design for molded ice cream, as shown.

In testimony whereof I have signed this specification,

ELMER J. MATHER.
